US00D915320S

(12) **United States Design Patent** (10) **Patent No.:** **US D915,320 S**
(45) **Date of Patent:** **** Apr. 6, 2021**

(54) **MOBILE PHONE**

(71) Applicant: **HUAWEI TECHNOLOGIES CO., LTD.**, Shenzhen (CN)

(72) Inventors: **Kangle Xue**, Shenzhen (CN); **Bangshi Yin**, Shenzhen (CN); **Jiuliang Gao**, Shenzhen (CN); **Bin Yan**, Shenzhen (CN)

(73) Assignee: **HUAWEI TECHNOLOGIES CO., LTD.**, Shenzhen (CN)

(**) Term: **15 Years**

(21) Appl. No.: **29/659,455**

(22) Filed: **Aug. 9, 2018**

(30) **Foreign Application Priority Data**

Mar. 15, 2018 (CN) 201830095344.4

(51) LOC (13) Cl. **14-03**

(52) U.S. Cl.

USPC ..... **D14/138 G**

(58) **Field of Classification Search**

USPC ..... D14/138 G, 138 AD, 341, 138 R, 496, D14/203.1, 203.3, 203.5, 203.7, 248, 371, D14/374; 455/575.1, 556.2; D21/517; 361/679.3, 679.56

CPC . G06F 1/1626; H04M 1/0266; H04M 1/0202; H04M 1/026

(57) **CLAIM**

The ornamental design for a mobile phone, as shown and described.

DESCRIPTION

FIG. 1 is a front perspective view of a mobile phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of portions of the mobile phone in FIGS. 1 through 7 represent environmental structure and form no part of the claimed design.

1 Claim, 7 Drawing Sheets
